Application November 28, 1934, Serial No. 755,168
In Switzerland March 17, 1934

5 Claims. (Cl. 261—44)

In carburetors for internal combustion engines the proportion of the volume of air to the engine speed is referred to as the air curve, and the proportion of the quantity of liquid fuel to the engine speed is referred to as the fuel curve. It is considered that the ideal condition is reached when the proportion of fuel to air over the whole range of the revolutions of the engine remains constant, so that the fuel curve and the air curve are in substantially the same relationship through the range of engine speeds. This condition could hitherto not be attained in practice and variations in the proportions of fuel and air in the mixture occurred. In practice this means that the best performance is not obtainable from the engine throughout its range of speeds.

It has been proposed temporarily to overcome this disadvantage by providing a fuel accelerating pump, or automatic air valves. However, these arrangements had the disadvantage that they adversely influenced the fuel consumption.

The present invention is concerned with carburetors having a spring loaded mushroom valve arranged in the choke tube and carried by a hollow stem slideable on a tubular member through which fuel is admitted to the choke the area of which is variable in accordance with the air flow and in which the vacuum necessary for the delivery of the fuel is taken from the choke, and it has for its object to provide an arrangement which will satisfy the condition set forth above.

With this object in view the invention comprises the provision at the upper end of the tubular member of an ante-chamber into which a damped pipe line from the float chamber enters above the fuel level and from which a further damped pipe line opens into the atmosphere.

In order that the invention may be more clearly understood two particular embodiments thereof will now be described by way of example, with reference to the accompanying drawing wherein:—

Figure 1 is a sectional view of one embodiment of the invention and Figure 2 is a similar view of a further embodiment.

Referring to Figure 1 of the drawing the fresh air is drawn in the usual manner through a pipe 2, chamber 7, choke tube 6, chamber 3 and throttle 4 into the inlet pipe 5 of the engine. The choke tube 6 is closed by a mushroom valve 8 which is subject to the action of a spring 9 which tends to hold said valve in closed position. The valve 8 has a hollow stem 10 the upper end of which is provided with an abutment 14 for the spring 9

and slides on a tubular guide member 11 secured to the carburetor casing. The abutment 14 may itself be formed as a valve to produce a damping effect. Secured to the valve member 8 is a needle valve 16 located in the tubular member 11 and 5 co-operating at its upper end with a jet 17 to vary the area of the opening of said jet.

The jet 17 divides the hollow space 12 from the hollow space 13 which serves as an ante-chamber into which opens the air pipe a and the 10 fuel pipe b from the float chamber 19. A further pipe c may also open into the ante-chamber 18, the other end of said pipe opening into the casing 15 between the throttle 4 and the engine. In the pipes a, b, and c restrictions or dampers x, y, and z 15 are provided.

In operation, owing to the aspirating action of the engine the mushroom valve 8 is automatically adjusted in the choke tube 6 in such a manner that the annular space between said choke tube 6 20 and the valve 8 hereinafter referred to as choke tube area, takes up a position under the combined action of the air speed and the spring 9 which affords passage to the air drawn in, such air having a certain minimum speed. Due to the 25 air speed at any given time and the corresponding vacuum in the choke tube area an aspirating action becomes effective in the space 18 through the channel 13, the hollow space 12 and the jet 17, whereby the fuel is drawn into the chamber 18 30 from the float chamber 19 through the pipe b and the restricting jet z. These normal processes are insufficient to secure that the fuel and air curves are maintained in the same relationship throughout the range of engine speeds, this being achieved 35 in the following manner:—

During the movement of the needle valve 16 the area of the opening in the jet 17 is varied according to the position of the mushroom valve 8 in the choke tube 6 and the corresponding position of the needle point 16 in the jet 17, owing to the fact that the needle has a conical end. The result is that the aspirating action which causes the fuel to be drawn in is varied according to the area of the opening. The air curve is 45 therefore determined by the form of the choke tube 6 and the spring 9 and the fuel curve is determined by the form of the point of the needle 16, that is by the various areas of the opening in the jet 17 which correspond to the 50 positions of the valve 8 and are determined by the needle point. In order to compensate for the effects of the resulting friction of the parts atmospheric air is admitted into the ante-chamber 18 through the pipe a and a restriction 55

or damper x , whereby the vacuum in the chamber 18 falls to a certain extent. As a result the vacuum in the chamber 18 never reaches the same value as in the annular choke area between 6 and 8 whereby undue enrichment of the fuel curve owing to the variable area of the opening between the jet 17 and needle 16 is prevented. This action may also be explained as follows:—

10 In the idle running position of the throttle the choke tube area and the area of the opening between the jet 17 and needle 16 are at their smallest. When the throttle 4 is opened the vacuum in the chamber 3 is increased. The valve 8 momentarily remains in the original position, whereby the vacuum in the choke area between 6 and 8 becomes effective through the channel 13 in the hollow space 12 . Owing to the considerably smaller cross sectional area of the opening 15 between the jet 17 and the needle 16 and to the secondary air entering through pipe a similar increase of the vacuum in the ante-chamber 18 is prevented, so that the supply of fuel to the space through pipe b is not accelerated to the 20 extent corresponding to the increase of vacuum in the choke area between 6 and 8 and no waste of fuel occurs. If now the valve 8 succumbs to the aspirating action of the vacuum, that is if it descends the annular opening between the 25 members 6 and 8 that is the choke tube area, is increased, the needle point 16 descends and the area of the opening in the jet 17 is correspondingly enlarged, so that the vacuum may have a 30 correspondingly stronger action through channel 13 and hollow space 12 in the chamber 18 , whereby the amount of fuel is increased in accordance with the volume of air passing through the annular choke tube area $6, 8$.

Since during idling the secondary air entering 40 the chamber 18 through pipe a and restriction or damper x may, in certain circumstances cause the vacuum to sink below the value necessary for the fuel supply during idling, a pipe c having a restriction or damper y is provided, connecting 45 the air intake of the engine with the chamber 18 , so that by means of the pipe line suction at the intake of the engine increases the vacuum in said chamber 18 , so that the amount of fuel entering the chamber 18 through the pipe b is increased.

50 In practical constructions it may be desirable to dispense with the needle valve 16 , so that the variable annular space between the members 16 and 17 is non-existent. In this case the action 55 of this space is replaced by a jet having an opening of a constant area and the vacuum necessary for the supply of the fuel to chamber 18 is taken from a constant area choke tube disposed in front of the choke tube with a variable annular space between members 8 and 6 .

60 In this embodiment, illustrated in Figure 2 an annular space is formed between the choke tube 6 and the valve 8 that is the choke tube area, when said valve 8 descends. The choke area at s above the valve 8 , is variable, by means of a 65 suitably formed enlargement or thickening 22 formed at the lower end of the sleeve 10 the area of the opening at s varying according to the position of the valve 8 . The vacuum at s which 70 determines the fuel curve is thereby corrected, so that the fuel curve is determined in accordance with the air curve of the carburetor which in turn depends upon the dimensions of the choke area 6 and the strength of the spring 9 .

75 The jet 21 has a constant area. From the pipe

c a pipe g having a damper v leads to the narrowest part of the choke tube 20 .

In operation, owing to the aspirating action of the engine the valve 8 is automatically adjusted in the choke tube area 8 and assumes a position in accordance with the counter action of spring 9 which affords passage for the air drawn in, such air having a certain minimum speed. Due to the air speed at any given time and the corresponding vacuum in the choke area between 6 and 8 the fuel in the chamber 18 is drawn in through the channel 13 and the hollow space 12 past the jet 21 . The jet 21 also has the effect that the suction can only influence the delivery of fuel in the chamber 18 to a slight extent. 15

The vacuum necessary for the supply of the fuel and determining the amount of fuel is admitted to the choke tube 6 through damper v , pipe g , pipe c and pipe a of chamber 18 , reduced by the secondary air admitted through the 20 damper x and pipe f . The vacuum so created in chamber 18 draws fuel from the float chamber 19 . The damper v has for its object to prevent in the idling position of the carburetor when the vacuum in the choke tube 6 is no longer sufficient 25 for the delivery of the fuel, the admission of too much secondary air to the chamber 18 through pipe g and pipes $c-a$, so that the vacuum in the choke tube area $6, 8$ may reach the chamber 18 through channel 13 , hollow space 12 , jet 21 . 30 Should this vacuum in the chamber 18 prove insufficient for the supply of fuel while idling it is increased to the vacuum between the throttle 4 and the engine through the damper y and pipes c and a . 35

We claim:—

1. A carburetor for internal combustion engines, comprising a choke tube, a vertically disposed tubular member adapted to supply fuel, a spring loaded mushroom valve in said choke tube 40 and adapted to control the flow of air through said choke tube, said valve being slidable on said tubular member, means effecting communication between the choke tube and the tubular member whereby the vacuum necessary for the delivery 45 of the fuel is taken from the choke tube and fuel is discharged into said choke tube, means for varying the effective cross-sectional area of said tubular member in accordance with the air flow in said choke tube, said tubular member having 50 an ante-chamber formed in the upper end thereof, a float chamber adapted to contain fuel, a damped pipe line effecting communication between said float chamber and said antechamber whereby fuel is supplied to said tubular member, 55 and a damped pipe line open to the atmosphere and leading into said antechamber.

2. A carburetor as specified in claim 1 in which the said means for varying the effective cross-sectional area of said tubular member comprise 60 a needle valve located in the tubular member, said needle valve being operatively connected to the mushroom valve whereby the effective cross-sectional area of the opening between the said needle valve and the said tubular member varies 65 proportionately with the effective area between the said choke tube and said mushroom valve.

3. A carburetor as specified in claim 1, in which the mushroom valve has a hollow stem provided on its external diameter with a swelling located 70 where the stem enters the choke tube and the tubular member is provided with a constant area jet and a damped pipe line leading from the throat of the choke tube to the said antechamber.

4. A carburetor as specified in claim 1 having 75

2,021,554

the arrangement wherein the vacuum in the ante-chamber is increased when the carburetor is in the idle running position through a pipe which opens the antechamber to the depression between 5 the throttle and the engine through a restriction or damper.

5. A carburetor as specified in claim 1 in which the hollow stem of the mushroom valve is provided with an abutment for the spring, said abutment also forming a damping device.
